CLAIM

The ornamental design for a folding wardrobe, substantially as shown and described.

DESCRIPTION

FIG. 1 is a top, front and right side perspective view of a folding wardrobe, showing my new design;

FIG. 2 is a bottom, rear and left side perspective view;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view with folded state;

FIG. 10 is a perspective view with folded state;

FIG. 11 is an enlarged view of a portion indicated with numeric 11 in FIG. 1;

FIG. 12 is an enlarged view of a portion indicated with numeric 12 in FIG. 2;

FIG. 13 is an enlarged view of a portion indicated with numeric 13 in FIG. 4; and,

FIG. 14 is an enlarged view of a portion indicated with numeric 14 in FIG. 4.

The broken lines in the drawings show portions of the folding wardrobe that form no part of the claimed design. The dot dash dot broken lines depict the boundaries of the detail areas and form no part of the claimed design.

1 Claim, 14 Drawing Sheets
